UNITED STATES PATENT OFFICE.

ROBERT C. RUSSELL, OF PITTSBURGH, PENNSYLVANIA.

INDEX.

1,207,220.

Specification of Letters Patent.

Patented Dec. 5, 1916.

Application filed September 30, 1915. Serial No. 53,392.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Indexes; and I do hereby declare the following to be a full, clear, and exact description of the invention, such as will enable others skilled in the art to which it appertains to make and use the same.

This invention relates to improvements in indexes,—one object of the invention being to so construct and arrange an index as to facilitate the compact grouping of names in a manner to permit the ready locating of any name without necessity of searching through a great number of names.

A further object is to provide a simple index whereby the names may be grouped without depending solely upon given names and without recourse to vowels in the names.

With these and other objects in view, the invention consists in certain novel features of construction and combinations and arrangements of features as hereinafter set forth and pointed out in the claims.

My improvements may be embodied in book form of the "loose leaf" type, or they may be applied to a "card index".

In the accompanying drawings; Figure 1 is a view of a loose leaf book showing an embodiment of my invention; Fig. 2 is a view showing my improvements as applied to a card index, and Fig. 3 is a view showing the construction and arrangement of one group of cards.

Experience and investigation has demonstrated the fact that the vast majority of surnames may be indexed with sub-divisions according to key letters comprising but five consonants,—namely: "L", "M", "N", "R", "T",—and combinations of these consonants. There are, however, comparatively few names which could not properly be indexed under any of these sub-divisions, and these may be indexed under a "Miscellaneous" heading. Names of corporations may be indexed separately according to their initial letter.

I propose to make what may be termed a double grouping of names; either in a single book or single set of cards or in a number of books or several sets of cards. For instance, one book or set of cards may be

devoted to all names having the same initial letter, or a single book or set of cards may be employed for names having several different initial letters or all the letters of the alphabet as initial letters. In Fig. 1, I have shown a book arranged for names having initial letters, "R", "S", "T", "U" "V", and "W",—each group of pages being separated by a spacer 1, and the pages of the book are numbered consecutively.

In Fig. 1, the leaves of the book are shown as being ruled and designated to receive the names of grantors and grantees and the volume and page on which deeds are recorded, as well also as to dates on which such records were made. In the present instance, my improved index applies to the names of grantors only. On each leaf of the book (and also on the spacers 1 if desired) two key tables 2 and 3 are printed. The key table 2 contains all the letters of the alphabet and also the relative numbers of said letters. The key table 3 contains the consonant key letters "L", "M", "N", "R", "T", "Misc" and "Corp", and also the numbers corresponding to said key letters and designations,—the same being numbered consecutively 1, 2, 3, 4, 5, 6, 7.

Names are entered in the index first according to the initial letter. For instance a name having the initial letter "S" will be entered in the "S" book or group and "B" in the "B" book or group, etc., but aside from this general grouping, the initial letter is disregarded and the name will be entered in accordance with the key letter or letters which first appear in the name after the initial letter. For instance the name "Siegel" or "Sholes" or "Sloss" would be entered in the "S" book or group according to the key letter "L".

In order to locate any name in the book, the number of the initial letter is ascertained from the key table 2, and the number of the key letter in the name is ascertained from the key table 3 and suffixed to the number of the initial letter, the result being the number of the leaf of the book on which the name may be found. For example, the initial letter "S" in the name "Siegal" is "19" and the key letter "l" appearing in this name is "1". Thus the name "Siegal" is found on page 191. To further illustrate, the name "Vermillion" may be selected for search. The letter "V" is number 22 and the first key letter appearing after the ini-

tial letter is "R" which is numbered "4" in the key table 3. Thus the name "Vermilion" should be found on page 224.

When a book contains several groups of 5 initial letter names, each group may be provided with a tab 4 having the initial letter and its number thereon, as indicated in Fig. 1.

When my improvements are applied to 10 cards instead of leaves of a book each initial letter group of cards is subdivided into key letter groups, and the first card 5 of the initial letter group may be of a different color from that of the guide cards 6 of the 15 key letter groups;—while the cards 7 of each key letter group may be of a color contrasting with guide cards. The guide card of each initial letter group is provided with a tab 8 on which the initial letter and the 20 number corresponding thereto, are printed. Thus, in Fig. 2, the tab on the initial letter guide card has printed thereon the letter "S" and its number, 19. The guide card 5 also has printed thereon, the two key tables 25 2 and 3, and these tables may also be printed on the guide cards 6, if desired. The several guide cards 6 are provided with tabs 9, on which the key letters and numbers of the key table 3 are printed, successively. The 30 cards 7 of each key letter group are notched in such manner to expose names on several overlying cards as illustrated in Fig. 3.

In searching for a name in any main group, the searcher may select the initial 35 letter number; then apply thereto the key letter number as previously explained, and then read the initial letter number with the key letter number on the group of cards. For example, to find the name Shipman, or 40 Simen, or Symen or Symons, the searcher may add to the initial letter number "19", the key letter number "2",—thus reading "192" and by thus combining the numbers on the guide cards 5 and 6, the cards with 45 the names mentioned will be at once found.

If desired, the initial letters and key letters may be omitted from the guide cards, and the index operated in accordance with

the numbers as indicated on the two key tables.

Having fully described my invention what I claim as new and desire to secure by Letters-Patent, is:—

1. An index comprising a group of index elements provided with an initial letter designation and a number corresponding to the same according to the position of the letter in the alphabet, said series of index elements divided into sub-groups according to key letters L—M—N—R—T, and a key 55 comprising the said key letters and numbers corresponding to their position in the key,—the initial letter number and the key letter number being readable together to designate the position in the index where a name being searched may be found.

2. An index comprising a series of index elements provided with a guide having a tab designated to represent the initial letter of sur-names and the number of said letter 70 according to its position in the alphabet, said series of index elements divided into sub-groups provided respectively with guides having tabs designated to represent successively key letters L, M, N, R, T, and numbers 75 corresponding to said key letters.

3. An index comprising a series of index elements provided with a guide having a tab designated to represent the initial letter of sur-names and the number of said letter according to its position in the alphabet, said series of index elements divided into sub-groups provided respectively with guides having tabs designated to represent successively key letters L, M, N, R, T, and numbers 80 corresponding to said key letters, the insert elements of each sub-group being notched successively to expose names on several index elements simultaneously.

In testimony whereof, I have signed this 90 specification in the presence of two subscribing witnesses.

ROBERT C. RUSSELL.
